GUY L. MATTHEWS, OF CHICAGO, ILLINOIS, ASSIGNOR TO HARRY L. DIEHL, OF CHICAGO, ILLINOIS

METHOD OF AND APPARATUS FOR CLEANING GUT

Application filed January 2, 1929. Serial No. 329,914.

This invention relates to a method of and apparatus for cleaning gut and refers to a novel method of cleaning and an apparatus for cleaning gut which is much more expeditious, satisfactory and economical than hand cleaning.

Heretofore, gut which has been used for the manufacture of various gut products, for example sausage casings, tennis racket strings, musical instrument strings and surgical gut, has been cleaned by hand.

It is an object of this invention to provide a method of and an apparatus for cleaning gut for elimination of hand cleaning.

Another object of the invention is to provide an apparatus in which the gut is cleaned more economically, much better and in much less time than at present by hand.

A further object of the invention is to provide an apparatus in which a more uniform product is secured and in which less breakage occurs.

The above, other and further objects of the invention will be apparent from the following description, accompanying drawings and appended claims.

According to the invention the method consists in moving the gut and while so moving subjecting it to even and uniform wiping, then tensioning it and further washing and wiping the same. The apparatus includes a wiping roller having a plurality of axially extending radially projecting blades with the active parts of the blades which come in contact with the gut so fashioned as not to tear or cut the gut, sets of feeding and driving rollers move the gut thru the wiping roller with the feeding and driving rollers rotating in opposite direction from the direction of rotation of the wiping roller. An idler roller cooperates with the wiper for holding the gut thereagainst. The other rollers of the machine preferably have fabric surfaces.

An embodiment of the invention is illustrated in the accompanying drawings and the views thereof are as follows:

Figure 1 is an elevational view of the front of the illustrated machine embodying this invention.

Figure 2 is a vertical sectional view taken between the front and back sides of the machine of Figure 1.

Figure 3 is an elevational view of the back side of the machine.

Figure 4 is a top plan view of the machine of Figure 1.

Figure 5 is a fragmental end elevation of some of the blades of the wiping roller. This view is enlarged.

Figure 6 is an end view partially in section of the wiping roller and the idler cooperating therewith at the entrance end of the machine.

As shown on the drawings:

The machine illustrated comprises a plurality of structural elements including uprights 1, longitudinal top and bottom members 3 and 4 and intermediate longitudinal members 5 and 6. These members are secured together in any desired manner as by bolts or rivets. The frame structure is the same on both sides of the machine while end pieces, not shown, connect the ends of the machine to form a rigid frame.

A channel member 7 is arranged transversely of the machine at the entrance end thereof and spaced above the top frame members 3 by suitable structural elements. Tie rods 8 connected at one end at 9 to the channel 7 and at the other end at 10 to the upper frame members 3 serve to rigidify the channel 7 and its supported parts.

A wiper roll 11 is supported on a shaft 12 which shaft in turn is carried at one end in a bearing 13 which is suspended by bolts 14 from the channel 7. The other end of the shaft 12 is supported by a collar 15 which is carried in a frame member 16 secured to the frame structure and also to the channel 7. The collar 15 projects through the frame member 16 and is provided outwardly of the member 16 with a gear or sprocket 17 with which cooperates a sprocket chain 18.

The wiper roll 11 is of metal and is provided with a plurality of axially extending radially projecting blades 19. The blades are made with the active portions thereof which engage the gut as cambered at 20 so

as to exert a wiping action on the gut rather than a tearing or cutting action. The wiping roller 11 is arranged to rotate in clockwise direction as viewed in Figure 1, Figure 2 and Figure 5.

5 An idler roller 21 is supported on a shaft 22 which projects through the roller or is connected to the ends thereof, which shaft is carried in bearings supported in journals 23 fastened to arms 24 which arms are pivoted at 25 to the end members 1 of the frame structure at the entrance end of the machine. There are two such arms 24 one at each end of the cylinder 21 for yieldingly 10 supporting the roller 21 in cooperative association with the wiping roller 11. Vertically disposed springs 26 are arranged over rods 27 the lower ends of which rods are secured in longitudinal frame members 5 15 while the upper ends of said rods are fastened to the arms 24 carrying the roller 21. The springs 26 act against the under side of the arms 24 and normally maintain the idler roller 21 against the blades 19 of 20 the wiper roller 11. The rods 27 are arranged to pass through the frame members 5 as the arms 24 are oscillated about the pivots 25 as gut is passing between the wiper roller and idler roller as will be more fully 25 hereinafter explained.

A shaft 28 is supported in journals 29 carried in blocks 30 secured to the upper frame members 3 of the frame which shaft is transverse of the frame and ahead of the 35 wiper roller 11. A roller 31 is supported on this shaft and is provided with a fabric surface 32 which surface is formed of several plies of coarse material such as burlap or canvas. A sprocket 33 secured to the shaft 40 40 at the rear side of the machine and a sprocket chain 34 passes over the sprocket wheel 33.

The roller 31 is arranged to be driven in the direction of the arrow, that is in counter-clockwise direction as observed in Figures 45 1 and 2. The roller 31 is arranged in the frame in such manner that the lower portion of the surface thereof is approximately in line with the lower point of the wiping drum 11 and actually is shown as being 50 slightly below the drum 11. A roller 35 similar in all respects to roller 31 is carried by a shaft 36 supported in the upper ends of arms 37 which arms are pivoted at 38 to 55 the upper frame members 3. The arms 37 extend below the pivot 38. A sprocket wheel 39 is fastened to the shaft 36 at the back side of the machine and a sprocket chain 40 passes over said sprocket wheel 39. An- 60 other sprocket wheel 41 is supported on a stub shaft 42 which is in line with or forms a part of the pivotal connection 38 between the arms 37 and the top frame member 3.

The sprocket chain 40 passes over the sprocket wheel 39 and 41 for driving the roller

85 in clockwise direction as observed in Figures 1 and 2 and as indicated by the arrows in the figures.

Another roller 43 carried by shaft 44 which is journaled at 45 on the upper frame member 3 is arranged transversely of the frame parallel to the rollers 31 and 35 and with its shaft below the shaft 28 of the rollers 31. A sprocket wheel 46 is secured to the shaft 44 at the back side of the machine and a sprocket chain 47 passes over the sprocket wheel 46. Connected with drum 43 on the upper run of the sprocket chain 47 is another sprocket behind sprocket 41 on the shaft 42 for the purpose of rotating 30 sprocket 41 and thus driving drum 35.

Another roller 58 is supported on a shaft 59 carried in the upper ends of arms 60 which arms are pivoted intermediate the ends thereof at 61 to the upper frame members 3 of the frame. A sprocket wheel 62 is secured to shaft 59 at the back side of the machine for driving drum 58. A sprocket chain 63 passes over the sprocket wheel 62. A stub shaft 64 secured to the rear frame member 3 at the upper end of the frame and the same forms a part of or is in alignment with the pivotal point 61 connecting the arms 60 to the frame. This stub shaft 64 carries three sprocket wheels, one of which is shown at 65. The innermost of said sprocket wheels is engaged by the sprocket chain 63 for driving drum 58, the intermediate sprocket wheel is engaged by the sprocket chain 66 which drives the three sprockets on the stub shaft 64 while the outermost or sprocket wheel 65 drives a sprocket chain 67 which engages a sprocket wheel 68 on shaft 69 supported in the frame structure and which shaft carries a metallic drum having a serrated surface for the purpose of delivering the gut as the same issues from the machine to a proper receptacle.

A motor 71 is secured near the bottom of the frame and has its shaft 72 connected with two speed reducers 73 and 74. The speed reducer 74 drives through means of a train of gears inwardly of the same and not shown a sprocket 75 which is in mesh with the sprocket chain 18 driving the wiping roller 11.

The other gear reduction 73 actuates a sprocket 76 which engages a sprocket chain 77 passing over a large sprocket 78 supported on a shaft 79 by the frame. There are transverse shafts 80 and 81 arranged near the sprocket wheel 78 on shaft 79 which shaft is at the front side of the machine, that is the part shown in Figure 1 of the drawings, are intergeared by suitable gears 82 and 83 in mesh as clearly shown in Figures 1 and 2. The ends of these shafts at the back side of the machine carry respectively sprocket wheels 84 and 85, first of which drives sprocket chain 66 and the second of which is connected with a similar sprocket wheel on 130

the same shaft and placed inwardly thereof drives sprocket chains 34 and 47. A treadle 86 is pivoted at 87 to the lower front frame member 4 as observed in Figure 1 and has connected thereto intermediate its ends a link 88, the upper end of which is connected at 89 to an arm 90 of a bell crank which is pivoted at 91 to the intermediate frame member 5 while the other arm 92 of said bell crank is pivoted at 93 to one end of an adjustable link 94 which is connected at 95 to the inner ends of the arms 37 carrying the roller 35.

A second treadle 96 is pivoted at 97 to the lower frame member 4 and it in turn has connected intermediate its ends thereto a link 98 which is pivoted at 99 to one end of an arm 100 of a bell crank which bell crank is pivoted at 101 to the intermediate frame member 5. The other arm 102 of the bell crank is pivoted at 103 to one end of an adjustable link 104 which is connected at 105 to the inner ends of the arms 60 carrying the roller 58.

Intermediate the front and back frame members, a lever 106 is keyed to shaft 91 while a similar lever 107 is keyed to the shaft or pivot 101 of the second treadle mechanism. Each of the levers 106 and 107 is slotted at 108 and 109 respectively and sliding heads 110 and 111 respectively have pins 112 passing through the slots 108 and 109. Springs 113 and 114, each of which is secured at 115 and 116 to an intermediate frame member 6 at the other ends thereof connected to the heads 110 and 111 so as to so influence the link motion connected to the rollers 35 and 58 as to retain the same in normal position which is that shown in the drawings. These springs tend to oppose movement of the treadles 86 and 96.

A water pipe 117 is disposed over the top of the machine and above the rollers. Branch pipes 118 and 119 lead downwardly from said pipe 117 and terminate in transversely extending spray nozzles 120 and 121, the nozzle 120 being arranged to discharge against the blades 19 on the wiping roller 11 and the nozzle 121 arranged to discharge against the surface of the rollers 31. Another branch 122 leads downwardly to a spray nozzle 123 arranged to discharge against roller 43. Other spray nozzles may be arranged as desired.

The operation of the illustrated machine is as follows.

The pieces of gut to be cleaned are fastened together by being knotted at one end, thus forming a head. A receptacle A is arranged at the leading or entrance end of the machine and another receptacle B at the discharge end of the machine. A plurality of heads are placed in the receptacle A in which is a quantity of water. These heads 65 have of course been subjected prior to the

cleaning operation by the machine to some proper solution for removing certain elements undesired in the finished product and which elements cannot be removed by the cleaning operation such as herein contemplated either mechanically or manually performed.

The operator of the machine gathers several heads from the receptacle A and depresses treadle 86. A lever 124 is secured on pivot 87 of the treadle and is connected by means of a rod 125 to the front ends of the arms 24 carrying the idler roller 21. Depression of the treadle 86 into contact with a lever 24 and continued downward movement will lower the idler roller 21 out of contact with the wiper roller 11 so that the heads of gut may be inserted between the wiper roller 11 and the idler roller 21. The heads are carried forwardly against the under surface of the roller 31. Depression of the treadle 86 will swing roller 35 away from its contact against roller 31 as may readily be observed. The operator after

passing the heads of gut between the wiper roller 11 and the idler roller 21 and bringing the same against the under surface of roller 31 releases the treadle 86 to such an extent as to enable the springs 26 to return the idler roller to normal position which is pressing against the wiper roller 11. The idler roller 21 will hold the gut tightly against the blades 19 of the wiper roller 11. The motor 71 is then started and the mechanism of the machine put in operation. The wiper roller 11 is driven in clockwise direction as observed in Figure 1 while the roller 31 is driven in counterclockwise direction. The operator holds the heads tightly against the roller 31 so that rotation of this roller in counterclockwise direction will pull the gut between the wiper roller 11 and the idler roller 21 contrariwise to the movement of the wiper roller 11 thus effecting a tensioning of the gut. The cambered ends of the blades 19 and the wiping roller 19 remove the surplus fat as may be observed in Figure 5 and any dirt that there is on the gut by a wiping action rather than by a cutting or scraping. This has resulted in a

much cleaner product and has reduced the percentage of breakage due to manual cleaning a considerable extent. As soon as the moving ends of the heads have been passed around the rollers 31 a sufficient distance to be engaged by the roller 35, the operator then releases the treadle 86 whereupon the springs 113 move the roller 35 to a normal position which is that shown in Figure 1 and holds it tightly against the heads of gut between the rollers 31 and 35. The roller 35 is driven in clockwise direction so that a wiping effect takes place on the gut between the rollers 31 and 35. Application of the water spray through the nozzle 121 di-

rected against the roller 31 aids in cleaning the gut as the same is drawn between the rollers 31 and 35.

The movement of the machine passes the gut up over the rollers 35 whereupon the operator grasps the ends of the heads and leads the same downwardly under roller 43 depressing treadle 96 to remove roller 58 so that the heads of the gut may be led between the rollers 43 and 58. Water spray from nozzle 123 serves as a further washing operation in the operation of the machine. The heads of the gut after the same have been passed over the roller 58 are then brought against the serrated roller 70 whereupon said roller directs the gut strings into the receptacle B which when filled may be removed for further disposition of the gut.

The rollers 31, 35, 43 and 58 have fabric surfaces of burlap, canvas, and the like, for the purpose of absorbing water for aiding in cleaning the gut, as well as for wiping the same. The fabric surface on the roller 58 may if desired be increased in thickness which increase adds to the cleaning effect of the machine. The variation in thickness of the fabric peripheral surface of the roller 58 varies the peripheral speed of this roller with respect to its mate 43 to effect a wiping action on the gut passing between these rollers, and at the same time applying tension to the gut. The other rollers may have the peripheries varied in the same manner for increasing the wiping effect of the rollers on the gut passing through the various pairs of rollers.

Repeated demonstrations and operations of a machine made in accordance to this invention have resulted in the production of clean gut which is more thoroughly cleaned than by the hand method and in which the percentage of breakages is much less than in the hand method. Furthermore, utilization of the machine of this invention is many times faster than the hand cleaning process.

The machine is small and compact in form and sturdy in construction, and can be operated continually throughout the day, thus cleaning many times the quantity of gut than is possible to be cleaned by a single operator employing the hand process. But one attendant is necessary to operate this machine.

The machine has been illustrated and described as having two sets of rolls 31, 36 and 43 and 58. However, it is within the contemplation of this invention to arrange as many more or less rollers as circumstances may demand without departing from this invention.

Suitable trays may be disposed underneath the rollers for withdrawing the stray water to the receptacle B or A as the case may be. Furthermore, the machine may be incased by removable partitions as slide

members so as to make a pleasing and serviceable device.

The wiping roller 11 and its idler roller 21 serve to stretch the heads of the gut being passed therethrough so as to scrape the same uniformly. The rollers 31 and 35 press the gut to a greater extent thus assuring cleaning of every piece of gut there is in the heads being passed through the machine.

The gist of the invention resides in the movement of the gut and treating the gut by wiping motion rather than by a cutting or tearing motion and the cleaning and wiping of the gut subsequently to the first wiping effect by fabric surfaces.

The machine of this invention is especially useful in cleaning slit gut, as it takes off all of the threads present on the slit gut.

The provision of the idle roller 21 results in a product which is fluffier than the products scraped by hand and which is not as dry. Furthermore, the mucous lining on the inside of the gut is taken off cleanly without any remaining on the gut as the same is delivered from the machine.

The position of the driving wiping rollers 32, 35 and 43 and 58 being disposed as shown in the drawings, enables drawing the gut through the machine, that is, between the wiping roller 11 and the idler roller 21 with even tension so that practically no breakage occurs. This is due to the fact that the surface of the roller 32 and 35 is used for the purpose of drawing the gut beneath the wiping roller 11 and idler 21. The angular position of these rollers, as well as the large amount of surface contact present in the drawing operation, eliminates the extreme pressure between the rollers 31 and 35 so that there is no squeezing and consequent breakage of the gut. It will be observed that practically 180° of the surface of these rollers is available for pulling the gut through the machine. The same condition holds true with respect to rollers 43 and 58. Wrapping the gut about these rollers as before stated, aids in pulling the same through the machine without breakage, and at the same time, the slit gut strings are spread and separated so as to secure feeding on both sides of the strings. Were the driving rollers to be arranged so as to tightly grip the gut, the gut would be crushed and rendered ineffective for commercial use.

It has been found that feeding gut to the machine of this invention, it is possible to use cold water for the washing of the same, rather than hot water, which is necessary in the hand feeding process. This is due to the fact that the wiping roller 11 cleans the gut more effectively and that the driving rollers 31, 35 and 43 and 58 dampen the gut so that it is not dry as it is when scraped by

hand. Furthermore, the gut does not have to remain as long in the state of putrefaction necessary in hand cleaning when cleaned by the machine. The results of such shortening of time of putrefaction results in the prevention of odors with the necessary destruction of the gut. As a further result, the gut cleaned with this machine is much stronger, better, fluffier and withal more satisfactory than when the gut is cleaned by hand.

A further advantage of this machine resides in the fact that the small threads which are cleaned off of the strips of gut are washed from the driving rollers by the water stream directed against these rollers, thus providing at all times driving rollers with comparatively clean surfaces and on which there is no matting of the small threads necessarily present in the cleaning of gut.

This machine is capable of operation by one man, rather than by several men, and it is possible for one man to clean more thoroughly than by hand a much greater quantity of gut, which gut is cleaned in a more thorough and satisfactory manner.

The provision of burlap or web surfaces on the driving and cleaning rollers results in a better pulling of the gut through the machine, and also a better washing of the gut. As before stated, the threads are washed off of these rollers and the rollers are kept constantly wet, so that there is no crushing of the gut as the fabric or burlap surfaces of the rollers give to a slight extent should for chance a knot or matted condition of the gut occur as the head is being drawn through the machine.

This machine is especially adapted for use with split gut which has been found more than satisfactory for wiping the same for commercial purposes.

It will be observed that the cambered end 20 of the blades 19 on the wiper roll 11 provides three edges for feeding the gut, as may be observed from Figure 5. The action of the blades is such as to wipe off the foreign matter without tearing or cutting the gut. The blades 19 are shown as mounted on the roller 11 to extend radially from the face. It is of course possible to incline these blades slightly to the truly radial position shown in the drawings and accomplish the same results.

The advantages obtained from the use of this machine results in a better and cleaner gut, which is cleaned in a much shorter time, gut which is not broken or stretched, and which is not spoiled because of the long period of putrefaction necessary for hand cleaning. Furthermore, all of the threads are removed from the slit gut and the finished product is silkier and fluffier than that produced in any other manner.

The invention has been described herein more or less precisely, yet it is to be understood that changes may be made in the arrangement and proportion of parts and that equivalents may be substituted, all without departing from the spirit and scope of this invention.

The invention is claimed as follows:

1. The method of cleaning split gut and the like which consists in tying the strings of the split gut at one end into a head, exerting a pull on said head to initiate movement of the strings of the gut past a scraping position, subjecting the strings of the gut to a scraping action at said position and stretching and squeezing the strings of said gut after it is pulled past said scraping position.

2. The method of cleaning split gut and the like which consists in tying the strings of the split gut at one end into a head, exerting a pull on said head to initiate movement of the strings of the gut past a scraping position, subjecting the strings of the gut to a scraping action at said position and stretching, squeezing the strings of said gut after it is pulled past said scraping position, and washing the scraped gut strings to remove mucus and other undesirable matter therefrom.

3. The method of cleaning split gut and the like which consists in putting the gut under tension to advance it past a scraping position, yieldably subjecting the gut to a scraping action at said position in such a way as to control the tension on said gut so that detrimental strains are not imposed on the gut, and squeezing and stretching the gut after it is pulled by said scraping position.

4. In a cleaning machine for split gut and the like, means for advancing the gut past a scraping position, a scraper at said position and a yieldably mounted idler roller at said position for yieldably bringing the gut into scraping contact with said scraper and for controlling the tension on said gut so that detrimental strains are not imposed on the gut, said first mentioned means including rolls for squeezing and stretching the gut after it has passed said scraping position.

5. In a cleaning machine for split gut and the like, means for advancing the gut past a scraping position, a scraper at said position, a yieldably mounted idler roller at said position for yieldably bringing the gut into scraping contact with said scraper and for controlling the tension on said gut so that detrimental strains are not imposed on the gut, said first mentioned means including rolls for squeezing and stretching the gut after it has passed the said scraping position, and means for washing away the

mucus and other such matter loosened on the gut by the squeezing of the same.

6. In a cleaning machine for split gut and the like, means for advancing the gut past a scraping position, a scraper at said position and yieldably mounted means at said position for forcing the gut into scraping cooperation with the scraper and for controlling the tension on the gut, said first mentioned means including rolls for stretching and squeezing the gut after it has passed said scraping position, said rolls being supported and arranged in such a manner that substantially at least one half the periphery 10 of each roll may contact the gut passed therethrough for pulling the gut past said scraping position, and whereby slippage of the gut on said rolls is substantially prevented.

20 7. In a cleaning machine for split gut and the like, means for advancing the gut past a scraping position, a scraper at said position, a yieldably mounted idler roller at said position for yieldably bringing the gut into contact with said scraper and for controlling the tension on said gut so that detrimental strains are not imposed on the gut, said first mentioned means including rolls for squeezing and stretching the gut after it has passed 25 said scraping position, and means for actuating said rolls to exert a pull on said gut in an opposite direction to that of the movement of said scraper, said idler roller being actuated by its frictional cooperation with 30 said scraper at a speed sufficient to enable a substantial stretching of the gut commensurate with the tensile strength of the gut.

8. In a cleaning machine for split gut and the like, means for advancing the gut past 40 a scraping position, a scraper at said position and a yieldably mounted idler roller at said position for yieldably bringing the gut into scraping contact with said scraper and for controlling the tension on said gut so that 45 detrimental strains are not imposed on the gut, said first mentioned means including rolls for squeezing and stretching the gut after it has passed said scraping position, one of said rolls having a greater peripheral 50 speed than the other one in cooperation therewith to enable a rubbing action on said gut as it passes between said rolls.

9. In a cleaning machine for split gut and the like, means for advancing the gut past 55 a scraping position, a scraper at said position and a yieldably mounted idler roller at said position for yieldably bringing the gut into scraping contact with said scraper and 60 for controlling the tension on said gut so that detrimental strains are not imposed on the gut, said first mentioned means including rolls for squeezing and stretching the gut after it has passed said scraping position, 65 and means for moving one of said rolls away

from the other to enable the head or tied end of the split gut to be inserted therein, whereby the rolls may become effective to pull the split gut past said scraper.

In testimony whereof I have hereunto 70 subscribed my name at Chicago, Cook County, Illinois.
